UNITED STATES PATENT OFFICE.

CHARLES HAMMESFAHR, OF NEW YORK, N. Y.

ELECTRIC SIGN.

1,007,868.

Specification of Letters Patent. Patented Nov. 7, 1911.

Application filed June 2, 1911. Serial No. 630,746.

To all whom it may concern:

Be it known that I, CHARLES HAMMESFAHR, a citizen of the United States, and a resident of New York, county and State of New York, have invented certain new and useful Improvements in Electric Signs, of which the following is a full, clear, and exact description.

This invention relates more particularly to an electric sign for advertising and display purposes.

One of the principal objects of the invention is to provide a simple and efficient device which may be applied in a convenient position to the glass portion of a show window in such a way that different colored lights may be successively projected upon an advertisement in order to attract attention and to make the advertisement more impressive and effective.

Another object of the invention is to provide a device which may be readily made and which may be sold at a comparatively small cost.

A further object of the invention is to provide a device in which the advertisement may be placed directly upon the window and the colors projected thereon, and in which the heat from the lamp producing the light will also serve to operate a part of the device having the means for changing the colors on the advertisement.

A still further object of the invention is to provide simple and efficient means whereby the device may be supported upon an ordinary incandescent electric bulb so as to be rotatable thereon.

With these and other objects in view, the invention will be hereinafter more particularly described with reference to the accompanying drawings, which form a part of this specification, and will then be pointed out in the claims at the end of the description.

In the drawings, Figure 1 is a plan view of one form of device embodying my invention. Fig. 2 is a longitudinal section of the device, partly in elevation, taken on the line II-II of Fig. 1. Fig. 3 is a fragmentary detail plan view of a part of the supporting bracket. Fig. 4 is a transverse section taken on the line IV-IV of Fig. 3, showing the means whereby the bracket may be used to engage an electric lamp socket and to support the lamp thereon. Fig. 5 is a sectional

plan view through the means for changing the colors on the advertisement, said means in this case being in the form of a cylinder; and Fig. 6 is a plan view on a smaller scale showing the device differently located from 60 that shown in Figs. 1 and 2.

The window may have the usual plate glass 10, and mounted thereon in any suitable way is a body 11. This body contains the advertisement to be displayed, and may 65 be produced by printing, lithographing or otherwise on a thin transparent or translucent or other body, or by transfer means if desired. The body or advertisement 11 may be of any desired form and size and located convenient thereto, in this case under the same, is a base 12. The base 12 may be cemented or otherwise held to the glass 10 on the inner surface thereof, and in said base are two openings or recesses which are engaged by the downwardly bent ends 13 of a supporting bracket 14. The base 12 may be of wood, porcelain or any other material and the bracket 14 may be made of wire and in a single piece. This bracket has two arms 80 15 which lie in substantially the same plane, and at or near the outer end thereof is a socket 16 substantially cylindrical in form. From the socket 16 project arms 17 each of which has an upturned and substantially V-shaped end 18. The reach rods 17^a of the arms or supporting members 17 diverge outwardly and the ends 18 thereof are adapted to support a shade 19 which may be of opaque material, as paper, or may be in the form of a reflector if desired. This shade or member may have a slotted portion forming a band 20 which is adapted to fit over any one of the ends 18 of the supporting members 17 of said bracket, or the said shade 19 may be held thereto in any other preferred manner.

A lamp socket 21 may be connected to any suitable source of electric supply, and said socket has a reduced portion 22 as usual, which is adapted to fit into the socket portion 16 of the bracket 14, said socket portion being formed as a part thereof and extending downwardly, as at 23, so as to serve as a bearing means for the socket. The 105 rods 15 of the bracket 14 may be held together by a device or clip as 24 so as to clamp and hold the lamp socket, and this clip has a part 25 pivoted to one of the rods 15 and has a spring portion 26 to fit about or partly 110

about the other rod 15, and said clip has a handle portion 27 by which the same may be released from one of the rods 15 in order that the socket 16 may be spread far enough apart when the said clip is released to permit the shade or lamp to be readily removed or inserted into the socket 16, though, if desired, this clip may be dispensed with and the spring of the reach rods 15 depended upon for supporting the lamp. The lamp socket carries the usual globe 28 from which projects the usual teat 29 which in this case forms a bearing for a device 30. This device 30 is in the form of a cylinder though it may be polygonal or any other desired form, and said device is adapted to throw different colors of light upon the advertising body or element 11. The device 30 has a plurality of panels 31 and these panels may all differ in color as red, white, blue and yellow, and each panel may be made up of a series of colors, as for example the upper part being red, the center blue, and the lower part yellow, these colors alternating with respect to the colors of the other panels so that when the device 30 is rotated, as will be presently described, these colors will be successively projected upon the advertisement 11. The panels 31 form a part of a cylinder which may be divided by strips 33 both on the inside and outside thereof to separate one panel from the other, and said cylinder may be of glass, celluloid, or of any other transparent or translucent material through which the light may be projected on to the advertisement 11.

The upper end of the cylinder 30 may be provided with a cap 34 and this cap may be of metal or of any other suitable material provided with a central bearing portion 35 adapted to fit over the teat 29 of the lamp globe or bulb 28 so that the same may readily rotate thereon. A series of blades 36 extend radially from the center toward the outer surface of the cap and these blades are so formed that the heat from the lamp will create sufficient circulation of air through the cylinder so that as the same passes the blades, the device 30 will rotate about the lamp, thus causing the different colored lights to be projected on to the advertisement, the shade 19 or reflector if made in this form being positioned to protect the rest of the window or to shade other articles within the window and the light to be projected only where it is wanted.

In Fig. 6, the construction is substantially the same as that already described, except that the base 37 has lugs or ears 38 which may be secured by screws or otherwise to a wood portion 39 of the window. This form of device is used where it is not convenient or advisable to cement or otherwise attach the base directly upon the glass. In this

case, the shade or the reflector may be supported on one of the side supporting members 17 of the bracket instead of in the manner shown in Figs. 1 and 2.

It will be understood that other means than an electric lamp may be used for lighting purposes as well as means to rotate the light projecting device.

From the foregoing, it will be seen that a simple, efficient and effective device is provided whereby advertising matter may be displayed upon the show window; that said device is simple in construction and is inexpensive to manufacture; that said device may be readily placed in position; that the advertising matter may be changed at will and of any suitable character to indicate the goods to be displayed; and that said device may be readily made and placed in position for use.

Having thus described my invention, I claim as new and desire to secure by Letters Patent:—

1. In a device of the character described, the combination with an advertising body, of a bracket, supporting means for said bracket, a lamp supported by the bracket, a rotatable device pivotally mounted on and surrounding the lamp and adapted to project different colored lights upon the advertising body and a shade supported on the bracket outside of said rotatable device.

2. In a show window light, the combination with an advertising body adapted to be attached to the window glass, of a bracket, supporting means for said bracket, an electric lamp supported by the bracket, a rotatable device pivotally mounted on and surrounding the lamp and adapted to project in succession different colored lights upon the advertising body and a shade supported on the bracket outside of said rotatable device.

3. In a show window light, the combination with an advertising body located on the window, of a bracket, a base for said bracket, a lamp supported by the bracket, a rotatable device surrounding and supported by the lamp and adapted to project in succession different colored lights upon the advertising body and a shade supported on the bracket outside of said rotatable device.

4. In a device of the character described, the combination of a base, a bracket supported on said base, a shade supported on the bracket, said bracket having a socket, an electric lamp supported in the socket, an advertising body located at a distance from said lamp, and a rotatable device comprising a plurality of panels differently colored and made of material through which light may be projected, said rotatable device also having a blade portion forming a support for the device and held to a part

of the lamp, said rotatable device adapted to be rotated through the heat from the lamp.

5. In a device of the character described, the combination of a base, a bracket supported on said base, said bracket having a socket, an electric lamp supported in the socket, and a rotatable device comprising a plurality of differently colored panels and 10 a blade portion forming a support for the device and held to a part of the lamp, said rotatable device adapted to be rotated through the heat from the lamp.

6. In a device of the character described, 15 the combination of a base, a bracket sup-

ported on said base, a shade supported on the bracket, said bracket having a socket, a lamp supported in the socket, an advertising body located at a distance from said lamp, and a device comprising a plurality 20 of differently colored panels and held to a part of the lamp and adapted to be rotated through the heat therefrom.

This specification signed and witnessed this 31st day of May, A. D. 1911.

CHARLES HÄMMESFAHR.
